[57] CLAIM

The ornamental design of a handle for a knife, as shown and described.

DESCRIPTION

FIG. 1 is a perspective view of a handle for a knife in accordance with my design;

FIG. 2 is a front elevational view thereof;

FIG. 3 is a rear elevational view thereof;

FIG. 4 is a side elevational view thereof as viewed from the right side of FIG. 2;

FIG. 5 is a side elevational view as viewed from the left side of FIG. 2.

FIG. 6 is a top plan view of my design; and,

FIG. 7 is a bottom plan view thereof.

The broken line showing of the knife blade is for illustrative purposes only and forms no part of the claimed design.
